Atty.

UNITED STATES PATENT OFFICE.

JACOB WILLIAM KOHN, OF NEWARK, NEW JERSEY.

LOCK-STRIKE.

SPECIFICATION forming part of Letters Patent No. 298,861, dated May 20, 1884.

Application filed November 30, 1883. (No model.)

To all whom it may concern:

Be it known that I, JACOB WILLIAM KOHN, a citizen of the United States, residing at Newark, in the county of Essex and State of New Jersey, have invented certain new and useful Improvements in Lock Keepers or Strikes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to more readily and perfectly adjust a lock strike or keep to the lock of a door that has by sagging or warping carried said lock away from its proper relation to the strike.

20 It consists in the combinations and arrangements of parts substantially as will be hereinafter set forth, and finally embodied in the claim.

25 Referring to the drawings, in which like letters indicate corresponding parts in each of the several figures, Figure 1 is an elevation of a strike, partially in section; and Fig. 2, a longitudinal section of the same.

In said drawings, *a* represents the strike, constructed to engage with an inner plate, *b*, and work laterally thereon to and from the door-lock. Said inner plate, *b*, is slotted longitudinally, as at *c c*, to enable the strike to be adjusted vertically.

30 *d* is a bed-plate secured to the door-casing or other part of the doorway-trimming to receive the strike and inner plate, said bed-plate being stationary in its relation to said trimming, and providing a firm support to the

strike, so that the latter will not move from 40 its position when struck by the lock-bolt.

e e are screws adapted to hold the inner plate and strike in position, and *ff* are screws which secure the bed-plate to the doorway-trimming.

45 In arranging the parts the bed-plate *d* is first permanently secured in position; then the inner plate, *b*, is screwed down nearly to a bearing upon the bed; the strike is then adjusted upon the said inner plate, when the screwing 50 is continued until the parts are brought firmly into holding contact with one another, as will be understood. The screw-head being square as well as slotted, the said screwing process can be continued even after the strike is in 55 place. Should the "sagging" or warping of the door require a subsequent adjustment of the strike, all that becomes necessary is to loosen the screws and adjust the strike either vertically or horizontally, or both, as may be required, and then to again tighten the screws to bind the parts, as before.

60 Having thus described my invention, what I claim as new is—

65 In combination, the plate *b*, having vertical slots to receive the screws *e*, and the keeper or strike *a*, adapted to work horizontally upon said plate and vertically with said plate without changing the position of the screws, substantially as set forth and shown.

70 In testimony that I claim the foregoing I have hereunto set my hand this 22d day of November, 1883.

JACOB WILLIAM KOHN.
